EP	0306463 B1	10/1991

Primary Examiner — John Windmuller(74) *Attorney, Agent, or Firm* — Abel Schillinger, LLP;
Thomas H. Osborn(57) **CLAIM**

The ornamental design for a clip, as shown and described.

DESCRIPTION

FIG. 1 is a front perspective view of a clip;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines showing a portion of the clip are for
illustrative purposes only and form no part of the claimed
design.**1 Claim, 4 Drawing Sheets**(56)
